CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The oblique shade lines represent a translucent or transparent appearance. The broken lines within the shaded area represent tightening elements that form no part of the claimed design. The broken lines depicting the remainder of the shoe form no part of the claimed design.
